UNITED STATES PATENT OFFICE

2,098,856

MEAT TENDERER

Joseph E. Bridges, Independence, Mo.

Application May 22, 1937, Serial No. 144,275

3 Claims. (Cl. 17—30)

My invention relates to improvements in meat tenderers, more particularly upon the device forming the subject of the Letters Patent No. 1,400,413 granted to me June 14, 1921.

In the use of the device disclosed by the Letters Patent aforesaid, I have found that the metal at the angled connection between the frame or knife body and the round handle has a tendency to break when the device struck a bone or the like, and further that if the end of the frame remote from the handle struck the meat first, the strain on the metal would tend to break the frame at a position in proximity of the center thereof due to the elongated recessed portions in the frame lengthwise of the latter. It has also been found that the upstanding series of spaced projections disposed on the head portion of the frame do not allow free action of the curved controlling spring for the cleaner element since such projections have permanently aligned contact with the under face of the spring.

It is therefore an important object of this invention to construct the handle of the tenderer and disposed in such relation with respect to the frame or knife body that the possibility of breaking off the handle under any working conditions is substantially eliminated.

A further object of the invention resides in the construction of the frame of a meat tenderer or chopper, wherein a plurality of upstanding projections for reinforcing the top of the frame are normally out of contact with the cleaner element controlling spring to allow for the free action of the spring at all times.

The invention further aims to provide in a manner as hereinafter set forth, a unit in the form of a combined handle and frame or knife body for use in devices of the class referred which is extremely durable, rigid, simple in construction, thoroughly efficient in use and comparatively inexpensive to manufacture.

With the foregoing and other objects in view, the invention consists of a novel construction, combination and arrangement of parts as will be more specifically referred to and as illustrated in the accompanying drawing wherein is shown an embodiment of the invention, but it is to be understood that changes, variations and modifications may be resorted to which fall within the scope of the invention as claimed.

In the drawing:

Figure 1 is a front elevational view of the assembled device,

Figure 2 is a fragmentary view similar to Figure 1 with one of the cutting knives removed,

Figure 3 is a sectional elevational view taken on lines 3—3, Figure 2,

Figure 4 is a sectional elevational view taken on lines 4—4, Figure 2,

Figure 5 is a sectional elevational view taken on lines 5—5, Figure 2,

Figure 6 is a fragmentary plan view taken on lines 6—6, Figure 2,

Figure 7 is a sectional elevational view taken on lines 7—7, Figure 2, and

Figure 8 is a sectional elevational view taken on lines 8—8, Figure 1.

With reference to the drawing, the meat tenderer or chopper generally indicated at 2 includes a horizontally disposed handle 4 formed of a panel-like body part 4^a and a reinforcement 4^b in the form of a split band extending throughout the top, bottom and rear end edges of body part 4^a. The band and body part are set up from a unitary metallic casting. The band is so disposed with respect to the top, bottom and outer end edges of body part 4^a to provide oppositely disposed laterally extending flanges through the top, bottom and rear end edges of the member 4.

The latter is formed of a horizontally disposed rear portion 4^c and a depending rearwardly inclined forward portion 6 forming a flush continuation of the inner end of the portion 4^c. The portion 4^c is of greater length than that of portion 6. The forward end of the portion 6 merges into the outer face of a tubular vertical bearing forming a part of a carrier or frame 8 to be referred to. The width of the rear end of part 6 is greater than the height of said bearing.

The handle 4 in vertical section at any part through its length is of I-beam contour. It will be noted that the angle of inclination of portion 6 is approximately 45 degrees with respect to the bearing into which it merges, at which angularity the strain on the metal forming the portion 6 is materially increased in order to prevent breakage of the handle from the frame.

The carrier or frame 8 constitutes what may be termed a knife body and it includes a wide flat horizontally disposed apertured head 10, a blade spacer portion 12 integral with the lower face of, depending from and of less thickness and length than that of head 10, and a pair of vertically disposed tubular bearings 14, 16 arranged at the ends of portion 12 and merging at their upper ends into the lower face of head 10. The head 10 forms a continuation of the upper end of and is of the same width as the band 4^b. The forward end portion 6 of handle 4 merges into bearing 16 and head 10 and is flush with the inner

ends into the lower face of head 10. The head 10 forms a continuation of the upper end of and is of the same width as the band 4^b. The forward end portion 6 of handle 4 merges into bearing 16 and head 10 and is flush with the inner

ends into the lower face of head 10. The head 10 forms a continuation of the upper end of and is of the same width as the band 4^b. The forward end portion 6 of handle 4 merges into bearing 16 and head 10 and is flush with the inner

end of bearing 16 and upper face of head 10. The openings provided by the bearings 14, 16 are indicated at 18, 20 respectively.

The device includes a vertically movable cleaner element 21 in the form of a U-shaped bar 22, having its sides or leg portions 24, 26 extending upwardly through the bearings 14, 16 and head 10. The element 21 is slidably relative to the carrier or frame 8. The element 21 is connected to frame 8 by suitable fastening means 28 arranged over the ends of head 10 and attached to the upper ends of sides or legs 24, 26 of element 21.

The U-shaped bar is free to reciprocate vertically in the bearings 14, 16, but the bar is restricted in its vertical movement by a slightly convex spring 30 which at its extreme ends overlie the fastening means 28 on the sides or legs of the bar 22. The central portion of the spring 30 is adapted to normally overlie a threaded recess 32 (Figure 5) formed in an upstanding circular projection 34 on and at the transverse median of the head 10 of the frame 8. The central portion of the spring 30 has an aperture 36 through which extends a threaded bolt 37 or the like for engaging in the threaded recess 32. A cap-like retaining member 38 having downwardly extending sides 40 is interposed between the head of the bolt 37 and the spring 30 in order to retain the spring 30 in proper alignment with the legs 24, 26 of the U-shaped cleaner bar 22. The head 10 immediately adjacent the projection 34 has a pair of upstanding projections 42 in proximity to the projections 34 for the purpose of reinforcing the frame 8 centrally thereof. It will be noted that the projections 42 do not extend vertically upward as far as the projection 34. This is so that they will normally remain out of contact with the under face of the spring 30 in order to allow for a free movement of the spring at all times.

40 The reduced depending portion 12 of the frame 8, Figure 2 has formed in its front and in its rear face a pair of oppositely disposed depressions 44, each arranged between the vertical median and an end of said portion 12. Each depression 45 gradually increases in depth from its outer to its inner end. These depressions or grooves tend to give some resiliency to the frame 8 without weakening the frame at the center thereof. The portion 12 is also apertured at 46 and 47 for alignment with apertures 46^a and 47^a respectively in a pair of cutting knives 48 and 50 positioned against the front and rear of portion 12 and abutting head 10. The knives 48 and 50 are identical in construction and are provided with like spaced 55 teeth 52 having sharpened cutting edges 54 at the ends thereof. The knives 48 and 50 are mounted on the portion 12 in oppositely disposed relation in order that the teeth of one knife will be arranged in staggered relation with respect to the 60 teeth of the other. The respective knives 48 and 40 are secured to the portion 12 of the frame 8 by threaded bolts 58 and cooperating nut 60 which extends through the aligned apertures 46, 46^a, 47, 47^a. It will be noted that an ear 62 is 65 formed on the reduced portion 12 adjacent the aperture 47 and the point connecting the bearing 16 and the portion 6 of handle 4. This ear 62 is for the purpose of reinforcing the frame 8 to prevent any possibility of the meat tenderer 70 cracking or breaking at that point under working conditions.

Referring to Figures 3, 4, and 5, it will be seen that the respective knives 48 and 50 are in abutting relation with the enlarged head 10 as shown 75 at 66 which further prevents the movement of

the knives with respect to the frame and also reduces to a minimum, the shearing stress on the threaded bolts 58. It will, of course, be readily apparent that the threaded bolts will permit the knives to be cleaned or the teeth to be sharpened without in any way necessitating the removal of the cleaner bar or the spring. Similarly, the spring may be removed without the removal of the knives.

From the foregoing, it will be apparent that 10 applicant has disclosed a novel structure in a meat tenderer or chopper which is durable and strengthened at all possible shearing points of the frame member to prevent any fracturing or breaking of the frame or handle under ordinary 15 working conditions.

What I claim is:

1. In a meat tender a knife carrier formed of a depending portion, a head and a pair of tubular bearings integral with the ends of said portion, said head being integral with one end of said bearings and formed with openings having their walls registering with the inner faces of the bearings, the width of the head being greater than the thickness of said portion, a horizontally disposed handle member of I-shaped contour in transverse cross section at any point throughout its length and disposed on its lower lengthwise edge, said member including a downwardly inclined forward portion having its forward end integral throughout thereof with one end of said head and one of said bearings, said head forming a flush continuation of the upper lengthwise edge of said member, the lower lengthwise edge of said member being flush with the bottom of the said bearing, and said carrier including a pair of outer lugs and an inner lug, said lugs being arranged in spaced relation, said lugs being integral with the upper face of said head, the pair of outer lugs being of less height than the inner lug, the latter being formed with a threaded socket and disposed at the transverse median of the head. 30

2. In a meat tenderer a knife carrier formed of a depending portion, a head and a pair of tubular bearings integral with the ends of said portion, said head being integral with one end of said bearings and formed with openings having their walls registering with the inner faces of the bearings, the width of the head being greater than the thickness of said portion, a horizontally disposed handle member of I-shaped contour in transverse cross section at any point throughout its length and disposed on its lower lengthwise edge, said member including a downwardly inclined forward portion having its forward end integral throughout thereof with one end of said head and one of said bearings, said head forming a flush continuation of the upper lengthwise edge 40 of said member, the lower lengthwise edge of said member being flush with the bottom of the said bearing, and said carrier including a pair of outer lugs and an inner lug, said lugs being arranged in spaced relation, said lugs being integral with the upper face of said head, the pair of outer lugs being of less height than the inner lug, the latter being formed with a threaded socket and disposed at the transverse median of the head, and said portion being formed in its front and back with a pair of oppositely disposed depressions lengthwise thereof, each of said depressions gradually increasing in depth from its outer to its inner end, the inner ends of said depressions being ar- 70 75

ranged between the vertical median and the ends of said portion.

5. 3. In a meat tenderer, a horizontal knife carrier disposed on one of its lengthwise edges and having its front and back formed with a pair of oppositely disposed spaced endwise aligned depressions lengthwise thereof, each of said depressions gradually increasing in depth from its outer to its inner end, said depressions being ar-

ranged between the vertical median and the ends of the carrier, and a horizontal handle member of I-beam form provided with a forward downwardly inclined portion integral at its forward end with one end of said carrier, the lengthwise edges 5 of said member being flush with the lengthwise edges of said carrier.

JOSEPH E. BRIDGES.
